[57] CLAIM

The ornamental design for a ski storage rack, as shown and described.

DESCRIPTION

FIG. 1 is a top perspective view of a ski storage rack showing our new design;

FIG. 2 is a front elevational view thereof;

FIG. 3 is a top plan view thereof;

FIG. 4 is a bottom plan view thereof;

FIG. 5 is a left side elevational view thereof, the right side being a mirror image; and,

FIG. 6 is a front elevational view of an alternate embodiment thereof, the only difference residing in the addition of another two pair of prongs.

FIG. 1

FIG. 2

FIG. 5

FIG. 3

FIG. 4

FIG. 6
